UNITED STATES PATENT OFFICE

OKLA H. HERSHMAN, OF INDIANAPOLIS, INDIANA

DESIGN FOR A FILLING DEVICE FOR CIGAR LIGHTERS

Application filed April 24, 1929. Serial No. 30,994. Term of patent 3½ years.

To all whom it may concern:

Be it known that I, OKLA H. HERSHMAN, a citizen of the United States, residing at Indianapolis, in the county of Marion and State of Indiana, have invented a new, original, and ornamental Design for a Filling Device for Cigar Lighters, of which the following is a specification, reference being had to the accompanying drawing, forming part thereof.

In the drawing, Figs. 1 and 2 are front and side elevations respectively of the filling device for a cigar lighter, showing my new design.

I claim:

The ornamental design for a filling device for cigar lighters, as shown.

In witness whereof, I have hereunto set my hand at Indianapolis, Indiana, this 20th day of April, A. D. one thousand nine hundred and twenty-nine.

OKLA H. HERSHMAN.
